(57) CLAIM

We claim the ornamental design for a wearable visual sensor and transceiver apparatus, as shown and described.

DESCRIPTION

FIG. 1 is the front elevation view of a wearable visual sensor and transceiver apparatus in accordance with the ornamental design;

FIG. 2 is the right side elevation view of a wearable visual sensor and transceiver apparatus in accordance with the ornamental design;

FIG. 3 is the left side elevation view of a wearable visual sensor and transceiver apparatus in accordance with the ornamental design;

FIG. 4 is the rear elevation view of a wearable visual sensor and transceiver apparatus in accordance with the ornamental design;

FIG. 5 is the top view of a wearable visual sensor and transceiver apparatus in accordance with the ornamental design;

FIG. 6 is the bottom view of a wearable visual sensor and transceiver apparatus in accordance with the ornamental design;

FIG. 7 is the perspective view of a wearable visual sensor and transceiver apparatus in accordance with the ornamental design;

FIG. 8 is the front elevation view, as worn, of a wearable visual sensor and transceiver apparatus in accordance with the ornamental design;

FIG. 9 is the right side elevation view, as worn, of a wearable visual sensor and transceiver apparatus in accordance with the ornamental design;

FIG. 10 is the left side elevation view, as worn, of a wearable visual sensor and transceiver apparatus in accordance with the ornamental design;

FIG. 11 is the rear elevation view, as worn, of a wearable visual sensor and transceiver apparatus in accordance with the ornamental design; and,

FIG. 12 is the perspective view, as worn, of a wearable visual sensor and transceiver apparatus in accordance with the ornamental design.

The human head that is depicted in FIGS. 8–12 is for illustrative context purposes only and forms no part of the claimed design.
